UNITED STATES PATENT OFFICE.

BERNHARDT HAUPT, OF BROOKLYN, NEW YORK.

ELECTRIC-LAMP SOCKET.

Application filed May 10, 1926. Serial No. 108,100.

This invention relates to a socket for decorative electric lamps such as those used on Christmas trees, and aims to simplify and improve the construction of such sockets. 5 The invention provides a fixture having a threaded socket for receiving a lamp and a threaded collar for holding an ornamental globe, the whole being formed of relatively few parts so made that they can be easily 10 assembled.

While I have disclosed a preferred embodiment for purposes of illustration, it should be understood that various changes may be made in the structure without departing 15 from the spirit and scope of the invention as hereinafter described and claimed.

In the drawings;

Fig. 1 is a cross section through the socket showing a fragment of the globe; 20 Fig. 2 is an elevation of a modified socket, the collar being shown in section.

Referring more specifically to the drawing, the main part of the socket is composed of the barrel 10 formed from a continuous 25 tube of conducting material, such as brass or copper. The lower part 11 of the barrel is formed with a screw thread of a size to receive the threaded end of an electric bulb 12. The upper end of the barrel is reduced 30 in size and formed with an external screw thread adapted to fit into a socket of a conventional type.

An insulating plug 14 is inserted in the upper end of barrel 10 and an insulating disc 35 15 is placed within the barrel between its ends. A lead wire 16 passes through plug

14 and disc 15 and is attached to a metal cap 17 above the plug and to a cap 18 below the disc.

The collar piece is formed to fit closely 40 about the barrel and has a disc portion 20 and an upstanding flange 21, the latter being screw threaded to receive the threaded part of an ornamental globe 22. The lower end of barrel 10 is pressed outwardly to form 45 a flange 23 extending below the disc portion 20 and to which the latter is soldered.

In the modification shown in Fig. 2 the disc member is soldered to the barrel 10 near its center and carries the flange 21 in 50 a depending position.

It will be evident that this construction provides a socket of few parts and simple construction that can be economically manufactured. 55

I claim:

An electric lamp fixture comprising a barrel formed from a single piece of sheet metal, the upper end of the barrel being reduced and having an external thread to form an 60 attaching plug, the lower part of the barrel being formed into a socket, a conductor insulated from the barrel and extending from the bottom of the socket to the top of the plug, a collar surrounding the barrel and 65 having an upwardly extending threaded flange spaced from the barrel, an outturned flange on the lower end of the barrel, the collar being secured against the outturned flange. 70

In testimony whereof I affix my signature.
BERNHARDT HAUPT.
